GLASS FIBER DRAWING APPARATUS

Joseph F. Courtney, Evanston, and Adelbert C. Radtke, Oak Park, Ill., assignors to International Harvester Company, a corporation of New Jersey

Application July 12, 1951, Serial No. 236,415

16 Claims. (Cl. 49—17)

This invention relates to means for attenuating glass fibers and has particular reference to mechanisms adapted for continuous production of glass strands and the like.

Individual glass fibers are extremely fragile and even when associated into a strand demand delicate handling especially at the high speeds required for drawing it to a flexible fine texture.

These conditions have heretofore dictated designs which adversely affect the quality of the product. A general object of the invention is to devise a drawing assembly which obtains the required drawing rate while grasping the material lightly along lengthy sinuous surfaces.

A more specific object is to design a drawing apparatus incorporating a pair of opposed rolls with resilient or flexible surface areas which are adapted to assume an undulant contour when subjected to centrifugal forces pursuant to rotation of the rolls to grasp the material therebetween.

The invention further contemplates a novel distribution of the mass of the peripheral portions of the rolls to effect varying radial displacement by centrifugal force of the specific masses whereby to obtain an undulant contouring of the grasping surfaces of the rolls.

More particularly the invention contemplates alternating segments of lighter and heavier masses about the periphery in a medium of flexible material whereby the heavier masses will be bulged radially outwardly farther than the lighter masses to provide a substantially sinusoidal surface profile.

These and other objects of the invention will become more apparent from the specification and the drawings, wherein:

Figure 1 is a fragmentary side elevational view of one form of the invention with environmental components shown diagrammatically.

Figure 2 is a radial cross sectional view taken substantially on the line 2—2 of Figure 1, and

Figure 3 is a fragmentary side elevational view of another form of the invention.

Describing the invention in detail and referring first to the embodiment shown in Figure 1, the furnace 2 which contains molten glass has a plate 4 at the bottom thereof provided with a plurality of apertured depending frustoconical bosses 6, 6 through which the molten glass is adapted to flow to form inverted cones of molten glass which upon initiation of the drawing process flow gravitationally to form a plurality of coarse filaments 8, 8, said filaments being initially gathered by an operator and trained over an applicator assembly 10 which is adapted to apply to each filament a suitable coating preferably of thermo-plastic or thermosetting types. The coated filaments are converged into a groove 12 of a gathering element or sheave 14 whereby the filaments are compacted and associated into a strand preferably while the coatings thereon are in an adherent state whereby the coatings may coalesce and form a unitary strand.

The strand 16 is entered between a pair of substantially identical drawing elements generally designated 18, 18 which are adapted to grasp the strand and impose a pulling force thereon thereby attenuating the filaments 8, 8 to attain desired characteristics. Each element 18 comprises an annular disc or structure 20 which is keyed to a driving shaft 22. The outer periphery of the structure 20 comprises a rim 24 to which is bonded a circumscribing annulus 26 which is formed of a flowable flexible material preferably soft rubber or other substance having

2

these characteristics and which is herein designated rubberlike. The annulus 26 has a plurality of regular circumferentially spaced apertures 28, 28 which are located preferably centrally intermediate the inner and outer margins thereof and within each aperture is disposed a rod 30 which is formed of material having greater density than that of surrounding portions of the annulus 26. The rods 30, which may be cylindrical steel shapes, have complementary fit within the openings 28 and are preferably fitted into a mold while the annulus is cast therearound to bind therewith.

It will be appreciated that centrifugal forces developed pursuant to rotation of the members 18 and the flexible characteristics of the annulus 26 of each thereof causes the annulus to expand radially outwardly whereby due to the differences in the densities of the rods and the adjacent sections of the annulus, the outer surface 32 of the annulus is caused to assume an undulant or scalloped contour as shown in phantom lines 20 which provides a substantially sinusoidal gripping surface for engaging the strand. In other words, the portions of the annulus in radial alignment with the heavier masses will be bulged out farther elongated more than those intermediate the masses thereby forming alternating crests and valleys. The arrangement of the opposed drawing rollers is such that at the grasping area of the rolls, the crest of each roll is meshed with a valley of the opposing roll whereby the strand which is gripped between the adjacent sections of the rolls is caused to sinuate therebetween 30 whereby an effective light grip is obtained on the strand along a relatively extensive length thereof while a pulling force is imposed on the strand pursuant to the rotation of the rolls. It will be appreciated that the frictional grip due to this interlocking of the strand with the rolls is accentuated and that the concentration of forces at a point or line contact on the strand, which is extremely destructive, is entirely eliminated. It will be noted that the members 18, 18 are, in static position, spaced apart so that an initial length of the strand may be safely positioned by the operator between the rolls prior to energizing the same.

Referring now to the embodiment shown in Figure 3, the drawing means generally designated 100, comprises a pair of substantially identical opposed rolls 102, 102 driven through shafts 104, 104 keyed thereto, each roll or wheel including a metallic preferably, steel, disc with a cylindrical rim 106 circumscribed by a composite flexible annulus generally designated 108. The annulus 108 is composed of a resilient flowable material comprising an outer ring 110 such as soft rubber with an inner section or ring 112 formed of harder durometer rubber or the like and of higher density than the ring 110. The ring 112 is formed with a cylindrical inner surface 114 which is bonded to the complementary outer side of the rim 106. The outer periphery of the ring 112 is of scallop-like, wavy sinusoidal contour whereby the ring 112 is formed with a plurality of lobes 116, 116 with intervening depressions 118. The inner face of the outer segment 110 of the annulus 108 has a complementary profile to the outer face at the segment 112 and is vulcanized thereto. In actual practice the inner and outer rings are cast to each other. The outer surface of each segment or ring 110 is cylindrical under static conditions. It will be readily appreciated that the characteristics of the mass or radial elongation of alternating segments of the annulus 108 are varied and that due to this condition and the centrifugal force the radial displacement of the alternating sections vary. This modifies the normally cylindrical outer surface of each section 110 and deflects the annulus 70 so that said outer surface is caused to assume a scallop-like or sinusoidal contour as shown in phantom lines in the drawings whereby at the grasping section of the rolls, the strand which passes therebetween is caused to be sinuated and interlocked with the drawing surfaces to obtain a more positive grip on the strand while it is being subjected to an attenuating pulling force. It will be noted that in static position, the cylindrical outer faces of the sections 110 of the opposed rolls are spaced so that the strand may be easily passed therebetween and that the centrifugal force expands the annuli 108 sufficiently to cause engagement therebetween at the grasping zone of

the mechanism 100. It will be noted that the drawing wheels 102, 102 are also arranged that the expanded and undulant outer surfaces of the annulus of each will mate with each other.

The expanded condition of each annulus is substantially as shown in Figures 1 and 3 in phantom lines.

What is claimed is:

1. In a material attenuating apparatus, a pair of annular, rotatable, opposed grasping members each having an imperforate, flexible, peripheral continuous annulus characterized by a predetermined varying mass distribution and under static conditions having a substantially cylindrical outer face, the variations in the mass effecting unequal expansion of the annulus during rotation thereof whereby distorting the cylindrical contour of the outer face thereof to provide an undulant contact area with the material adapted to be engaged by the face.

2. In a material attenuating apparatus, a pair of opposed annular members rotatable on generally parallel axes, each member having a solid radially and circumferentially continuous peripheral flexible annulus with an outer statically generally annular face, certain segments of the annulus being alternated with and formed and arranged to displace radially outwardly farther than others thereof under the influence of centrifugal force whereby distorting said face to scallop-like contour to provide curved grasping areas for interlocking contact with the material passing between the members.

3. In a fiber attenuating apparatus, a pair of opposed annular members rotatable on generally parallel axes and adapted to receive the fiber therebetween for grasping and drawing the same, each member having at least a peripheral annulus formed of soft rubbery substance, said substance having material of higher density bonded thereto and disposed inwardly of the outer fiber grasping surface thereof and formed and arranged to control outward bulging of the rubber whereby distorting said surface to undulant contour when said members are rotated and thereby causing fiber entered between said members to be engaged along curving areas.

4. In fiber attenuating apparatus, a pair of opposed, rotatable annular members spaced apart under static conditions and disposed to define a gap for receiving fiber adapted to be entered therebetween, each member being formed at least about its periphery of flexible, resilient material to provide an unbroken outer grasping surface, certain segments of the material having greater mass than and alternated circumferentially of the member with the remaining segments of the material whereby during rotation of each member, said material is caused to expand centrifugally with the segments of greater mass displaced farther radially outwardly than said remaining segments thereby changing the contour of said surface to assume a substantially sinusoidal profile adapted to engage the fiber, and means for rotating said members in profile interfitting relationship with each other at contiguous regions to close said gap and establish a grasping zone on the fiber for effecting sinuation and interlocking engagement therewith.

5. In fiber attenuating apparatus, opposed, rotatable, resilient drawing elements adapted for grasping contact with fiber entered therebetween, each element having a plurality of circumferentially spaced sections intercalated with and of different mass characteristics than the sections therebetween and formed and arranged to displace under centrifugal force radially outwardly farther than said sections therebetween to form a corrugated outer surface adapted for interlocking engagement with the fiber, and a band of flexible material of substantial thickness about the periphery of each element constituting said second-mentioned sections and of substantially constant characteristics throughout its length said first-mentioned sections being embedded in said band of material.

6. In a fiber attenuating apparatus, a rotatable element having at least a peripheral band formed of continuous, flexible, resilient material with regularly circumferentially spaced segments of predetermined substantially identical mass characteristics intercalated with and of different mass characteristics than the sections therebetween and formed and arranged to displace under centrifugal force radially outwardly farther than said sections therebetween to form a corrugated fiber-engaging outer surface, said segments being formed of material having a higher density than said sections.

7. In a fiber attenuating apparatus, a rotatable element having at least a peripheral band formed of continuous, flexible, resilient material with regularly circumferentially spaced segments of predetermined substantially identical mass characteristics intercalated with and of different mass characteristics than the sections therebetween and formed and arranged to displace under centrifugal force radially outwardly farther than said sections therebetween to form a corrugated fiber-engaging outer surface, said segments being formed of material having higher density than said sections and being confined wholly between the inner and outer peripheries of the element.
8. In a fiber attenuating apparatus, a rotatable element having at least a peripheral band formed of continuous, flexible, resilient material with regularly circumferentially spaced segments of predetermined substantially identical mass characteristics intercalated with and of different mass characteristics than the sections therebetween and formed and arranged to displace under centrifugal force radially outwardly farther than said sections therebetween to form a corrugated fiber-engaging outer surface, said segments being entirely isolated from one another and being floatingly supported by said band of material.
9. In a fiber attenuating apparatus, a rotatable element having at least a peripheral band formed of continuous, flexible, resilient material with regularly circumferentially spaced segments of predetermined substantially identical mass characteristics intercalated with and of different mass characteristics than the sections therebetween and formed and arranged to displace under centrifugal force radially outwardly farther than said sections therebetween to form a corrugated fiber-engaging outer surface, said segments being substantially cylindrical inserts within said material.
10. A rotatable material attenuating wheel having a center section with a scalloped outer contour including a series of circumferentially spaced lobes and depressions therebetween, and a band of distortable, flexible substance presenting under static conditions a cylindrical outer face, said band having an inner periphery complementary to said outer contour of the center section and intimately connected therewith along its entire circumferential extent, the portions of the band in the depressions being of greater mass than the portions on the lobes so that the former portions bulge radially outwardly farther than the latter portions pursuant to predetermined rotation of the wheel, whereupon said portions collectively develop an undulant peripheral material grasping profile.
11. In a material attenuating apparatus a substantially rigid core, an annulus surrounding the core and comprising an outer ring formed of soft flexible substance and an inner section of relatively hard rubber bonded directly to the core and having a scalloped outer contour bonded to a complementary inner face of said outer ring, said outer ring presenting under static conditions an outer substantially cylindrical surface.
12. In fiber attenuating apparatus, a rotatable, annular drawing element comprising a substantially rigid core, a flowable annulus circumscribing said core and bonded thereto and under static conditions presenting a substantially cylindrical outer surface, and regularly circumferentially spaced cylindrical metallic bonded inserts within said annulus intermediate the inner and outer peripheries thereof and oriented with their axes substantially parallel to the axis of rotation of the element.
13. In material attenuating apparatus, a pair of opposed, rotatable, flexible, resilient rolls, each roll statically presenting a substantially cylindrical outer surface, the outer layer of each roll being formed of relatively thick readily distortable rubber with heavier material embedded therein at regularly circumferentially spaced intervals, means for driving each roll whereby to expand said rubber to effect a grasping action on material entered therebetween, the spacing of said heavier material of each roll being arranged to enter between portions of the heavier material of the other roll at the areas of contact between the rolls.
14. In a glass fiber drawing element, a rotatable structure having an inner portion and an outer portion, said outer and inner portions united along complementary interfitting contours, said outer portion comprising a circumferentially continuous ring presenting an endless, continuous, material grasping face, said ring being formed of readily expansible and contractible substance varying uniformly in radial thickness inwardly of said

face about the entire circumferential extent thereof and providing relatively thick sections and intervening thin sections, said thick sections characterized by different radial elongation than said thin sections attendant to operational rotation of said structure whereby distorting the static contour of said substance and undulating said face.

15. For a glass fiber attenuating apparatus, a rotatable drawing structure comprising an inner section and a peripheral circumscribing ring thereabout presenting a generally cylindrical outer periphery under static conditions, said ring being of flexible, expansible and contractible substantially homogeneous material throughout, said ring and inner section having complementary interconnected mating surfaces, said ring having a first annular series of circumferentially spaced portions of predetermined radial depth arranged in alternating relationship with a second series of portions of substantially lesser radial depth, said first and second series of portions affording relatively different centrifugal displacement characteristics and collectively adapted pursuant to rotation of the wheel, to distort the cylindrical outer periphery of the ring to an undulant fiber engaging contour.

16. In a glass fiber attenuating apparatus, peripherally opposed co-operative rotatable drawing elements each having an integral outer annulus of readily deformable, expansible and contractible material, said elements being peripherally spaced from each other at adjacent regions

under static conditions and defining a fiber-receiving gap therebetween, said elements upon rotation at predetermined speeds effecting expansion of the annuli thereof and thereby closing the gap and grasping the fiber entered therein upon said elements being statically disposed, each annulus having inner and outer continuous peripheries and each annulus having the material thereof continuous radially between said inner and outer peripheries about its entire circumferential extent, and said annulus of each element constituted of regularly spaced segments having certain elongation characteristics and intervening sections of relatively different centrifugal elongation characteristics radially of said elements under the influence of centrifugal forces attendant to rotation thereof and collectively adapted to develop a continuous undulant peripheral contour, and means rotating said elements in phase relationship with each other to effect complementary mating of said undulant contours of respective elements at said regions.
